CLAIM

We claim the ornamental design for a bottle cap and fitment assembly, as shown and described.

DESCRIPTION

FIG. 1 is a top perspective exploded view of a bottle cap and fitment assembly showing our new design;

FIG. 2 is a bottom perspective exploded view thereof;

FIG. 3 is a front exploded view thereof;

FIG. 4 is a bottom perspective view of the bottle cap and fitment assembly of FIG. 1 shown in an assembled configuration;

FIG. 5 is a top view thereof;

FIG. 6 is a bottom view thereof;

FIG. 7 is a front view thereof; and,

FIG. 8 is a sectional view thereof taken in the direction of line 8-8 in FIG. 5.
